UNITED STATES PATENT OFFICE.

EDWIN CHARLES HESS, OF CAMDEN, NEW JERSEY.

TELEPHONE-RECEIVER.

SPECIFICATION forming part of Letters Patent No. 473,256, dated April 19, 1892.

Application filed July 1, 1891. Serial No. 398,111. (No model.)

To all whom it may concern:

Be it known that I, EDWIN CHARLES HESS, a citizen of the United States, and a resident of Camden, Camden county, New Jersey, have 5 invented certain Improvements in Telephone Receivers, of which the following is a specification.

The object of my invention is to so construct a telephone-receiver that it can be applied to both ears of the person using the receiver at one and the same time and to so construct the receiver that the ear-pieces will fit tightly to the ears, my improvements being readily attachable to the ordinary "Bell" receiver.

In the accompanying drawings, Figure 1 is a side view, partly in section, of my improved telephone-receiver. Fig. 2 is an enlarged face view, looking in the direction of the arrow, 20 Fig. 1. Fig. 3 is a section on the line 1 2, Fig. 2. Fig. 4 is a perspective view of the yokes of the connecting-arm. Fig. 5 is a modification of the universal joint. Figs. 6 and 7 are views of modifications of the joint between the 25 primary receiver and the connecting-arm, and Fig. 8 is a view of a modification.

A is the receiver of an ordinary Bell telephone-instrument having the usual binding-screws $a a$. The usual ear-piece has been removed and my improved ear-piece B substituted therefor. In the present instance this ear-piece is screwed upon the instrument and holds the diaphragm a' in place; but it will be understood that the ear-piece can be attached to the instrument in any suitable manner, and, in fact, in some instances may be applied directly to the ear-piece of the instrument where circumstances prevent the removal of the original ear-piece.

40 The ear-piece B has a central projection b , which is adapted to enter the ear, and in this projection is the opening c . Around the ear-piece is a cushion C, made in the present instance of a thin rubber tube, which will yield 45 and accommodate itself to the ear, so that when a person is receiving a message the ear is shut off entirely from outside noises.

Pivoted to the ear-piece B is an arm D. This arm D, as shown in Fig. 1, is yoked and 50 pivoted at $d d$ on each side of the receiver. The arm is sprung in place in the present instance; but screws or pins may be used as

pivots when necessary. The arm D is so bent as to pass over or back of the head of the person using the instrument and has at its opposite end a receiver E, provided with an ear-piece F, similar in form to the ear-piece B, having the cushion C and a projecting portion b . The receiver is connected to the arm by a universal joint e , and, as shown in Fig. 1, this 60 joint is made of a flexible tube, preferably of rubber, secured to the end of the arm and to a projection on the receiver; but the joint may be made as shown in Fig. 5, which illustrates a ball-and-socket joint.

65 The receiver E is provided with a diaphragm f and internal mechanism necessary for the transmission of speech.

The arm D and its yoke-section are hollow, and in this hollow arm are the wires $x x'$, 70 which make a circuit including the receiver E, the wires passing to the binding-posts e' on the receiver E, and their opposite ends pass out orifices $g g$ and along each side of the receiver A to their binding-posts a^2 , as clearly 75 shown in Figs. 1 and 2, the wires being so arranged that both receivers are in the same circuit.

The tubular arm D may connect with the space in front of the diaphragm of the receiver A through hollow pivots, as shown by dotted lines in Fig. 2, and also may connect with the space in front of the diaphragm f , Fig. 1. Thus in the event of the magnetic portion of the receiver E not working satisfactorily, the message may be carried through 85 the tube.

In Figs. 6 and 7 I have shown the joint between the ear-piece and the arm D in a slightly different manner from that shown in Fig. 1, 90 the yoke-section being dispensed with and the arm coupled to a bearing B' , having two projections, which enter the openings in the arm, the bearing being hollow for the passage of the wires from the arm, as clearly shown in 95 said figures.

In Fig. 8 I have shown a modification in which the magnetic portion of the receiver E is removed and connection is made between the space and front of the diaphragm of the 100 receiver A through the medium of a hollow tube b , the wires $x x'$ in this case being dispensed with. It will thus be seen that when my instrument is used both ears are sealed

against outside noises, the projections *b* entering the ear and the cushions *C* fitting snugly against the outer portions of the ear.

The arm *D*, carrying the receiver *E*, can be thrown back over the head and the instrument readily removed.

The universal joint between the arm *D* and receiver *E* allows the instrument to accommodate itself to the head of the user.

10 I have made the instrument so that it can be applied to the receivers now in common use; but a receiver embodying my invention may be made in which a special construction or arrangement of the portion *A* may be ad-
15 visable.

It will be understood that the cushion *C* may be made of other material than rubber and may be made different shape in cross-section.

20 I claim as my invention—

1. The combination, in a telephone-receiver, of the main standard receiver, to which the main wires are attached, an arm pivoted to said main receiver, and a second receiver carried at the opposite end of said arm, with wires passing through the arm from the main wires and attached to the opposite receiver, so that both instruments will be in circuit without disturbing the general arrangement of the 25 standard receiver, substantially as described.
2. The combination of the standard receiver as a main receiver, the ear-piece *B*, secured thereto, a hollow arm *D*, pivoted to the ear-piece *B*, with a receiver *E*, a universal joint 30 connecting the receiver *E* with the hollow arm, and an ear-piece *F* on the receiver *E*, with wires *xx'* passing from the standard receiver
35

through the arm *D* to the receiver *E*, substantially as described.

3. The combination of the main receiver *A* 40 with an ear-piece *B*, having a central projection *b*, adapted to enter the ear, a passage in said projection communicating with the space in front of the diaphragm of the main receiver, a hollow arm *D*, pivoted to said ear-piece and communicating with a space in 45 front of the diaphragm of the receiver *A*, with a receiver *E*, and a hollow projection *b* thereon adapted to the ear, said receiver being connected to the tubular arm *D*, thus forming 50 communication between the two receivers, substantially as described.

4. The combination of the receiver *A*, the yoked hollow arm *D*, an ear-piece *B*, to which the yoke is pivoted, a receiver *E*, having an 55 ear-piece *F*, and wires *xx'*, extending along the receiver *A* into openings *g g'* at the rear of the yoke-sections of the arm and passing through the arm to the receiver *E*, the whole arranged substantially as described. 60

5. The combination of the receiver, the ear-piece *B*, the central projection *b*, with passage therein communicating with the space in front of the diaphragm of the receiver, and a hollow annular cushion *C*, secured to the ear-piece and extending beyond the central projection *b*, substantially as described. 65

In testimony whereof I have signed my name to this specification in the presence of two subscribing witnesses.

EDWIN CHARLES HEISS.
